CASKET PLACER

Joseph Robert Smetana, Sedalia, Mo.

Application July 26, 1939, Serial No. 286,710

6 Claims. (Cl. 27—26)

This invention relates to a casket placer.

The invention aims to provide, in a manner as hereinafter set forth, a placer for conveniently positioning a casket relative to a lowering device, arranged over the grave for the casket.

The invention further aims to provide, in a manner as hereinafter set forth, a casket placer for facilitating the position of a casket relative to a casket lowering device disposed relative to a grave.

The invention further aims to provide, in a manner as hereinafter set forth, a casket placer for the purpose referred to capable of being removably positioned on a casket lowering device.

The invention further aims to provide, in a manner as hereinafter set forth, a casket placer for the purpose referred to capable of being readily assembled and disassembled and when assembled quickly installed with respect to a casket lowering device disposed over and about a grave.

The invention further aims to provide, in a manner as hereinafter set forth, a casket placer capable of being expeditiously assembled and disassembled and when disassembled stored in a comparatively small space.

The invention further aims to provide, in a manner as hereinafter set forth, a casket placer for the purpose referred to including means whereby the casket may be conveniently slid by the pallbearers to a position in relation to a lowering device therefor arranged at a grave.

The invention further aims to provide, in a manner as hereinafter set forth, a casket placer for the purpose set forth having means for releasably supporting it from, on and over a casket lowering device.

The invention further aims to provide, in a manner as hereinafter set forth, a casket placer for the purpose referred to capable of being adjusted relative to its length and width.

The invention further aims to provide, in a manner as hereinafter set forth, a casket placer for the purpose referred to including a frame capable of being adjusted to length and width and constituting a track forming means and a carriage slidably mounted on said means and capable of being adjusted relative to width.

The invention further aims to provide, in a manner as hereinafter set forth, a casket placer for the purpose referred to including track forming means for a slidable carriage having a vertically adjustable body and a supporting roller at the rear end of said means capable of being vertically adjusted to align with the body of the carrier.

The invention further aims to provide, in a manner as hereinafter set forth, a casket placer for the purpose referred to including means for positioning the casket on the bottom of a vault supported at the upper end of a grave by a lowering device common to the casket and vault.

The invention further aims to provide, in a manner as hereinafter set forth, a casket placer for the purpose referred to which is simple in its construction and arrangement, strong, durable, conveniently installed with respect to a casket lowering device disposed relative to a grave, thoroughly efficient in its use, quickly removed from said lowering device and expeditiously disassembled and comparatively inexpensive to manufacture.

Embodying the aims aforesaid and others which may hereinafter appear, the invention consists of the novel construction, combination and arrangement of parts as will be more specifically described and illustrated in the accompanying drawings, wherein is shown embodiments of the invention, but it is to be understood that changes, variations and modifications may be resorted to which fall within the scope of the invention as claimed.

In the drawings—

Figure 1 is a top plan view of a casket placer in accordance with this invention showing the adaptation thereof with respect to a casket lowering device,

Figure 2 is a side elevation of a casket placer in accordance with this invention showing the adaptation thereof with respect to a casket lowering device, the latter being partly shown in sections,

Figure 3 is a section on line 3—3 Figure 1,

Figure 4 is a section on line 4—4 Figure 1,

Figure 5 is a detail in longitudinal section of one end of the casket placer,

Figure 6 is a detail in transverse section,

Figure 7 is a top plan view of a modified form of a casket placer in accordance with this invention and further illustrating the adaptation of the placer with a casket lowering device, the placer being partly in section and the lowering device illustrated in dotted lines,

Figure 8 is a section on line 8—8 Figure 7,

Figure 9 is a section on line 9—9 Figure 8,

Figure 10 is a section on line 10—10 Figure 7.

Figure 11 is a cross sectional view illustrating the position of the carriage upon a vault base, and

Figure 12 is a cross sectional view of a modified form of track forming means.

Referring to Figures 1, 2, 3, 4 and 7 of the drawings, a casket lowering device of well-known

form is indicated at 1 and it includes a set of spaced supports 2 formed with flanges 3. The supports 2 extend into vertically disposed socket members 4 and with the flanges 3 of the supports 5 seated on the upper ends of the members 4. Binding screws 5 for the supports 2 are carried by the members 4. As is well-known a casket lowering device includes a pair of oppositely revoluble lengthwise adjustable shafts 6 from which unwind the lowering belts 7. The device 2 also includes lengthwise adjustable end members 8, each formed of a pair of telescopic sections 9, 10. The shafts 6 are also formed of a pair of telescopic sections 11, 12. The shafts 6 and end members 8 are connected to the supports 2. As is well-known a casket lowering device includes suitable means for operating the shafts 6 for the purpose of winding and unwinding the belts 7. The lowering device 1 as shown is provided with telescopic adjustable suspension rods 13 connected to the members 4, as at 14 for suspending green silk plush draperies, not shown at the side and end walls of the grave.

With reference to Figures 1 to 6, they illustrate a casket placer 15 in accordance with this invention and which includes a frame 15^a formed of a pair of side members 16 of like form; but oppositely disposed and a pair of end members 17 of like form, but oppositely disposed. The frame 15^a is adjustable relative to length and width. Each side member 16 is formed of a pair of sections 18, 19 of angle shape in transverse section to provide a vertical and a horizontal leg. The horizontal leg of the section 19 is formed lengthwise thereof with a row of closely related openings 20. The horizontal leg of the section 18 is formed with a set of openings 21, preferably three in number and equally spaced from each other. The section 18 of a side member 16 is mounted for a portion of its length upon the horizontal leg of the section 19. The outer end terminal portion of the section 18 is bent inwardly at an angle, as at 22. The outer end terminal portion of the section 19 is bent inwardly at an angle, as at 23. The openings 21 of the section 18 coat with selected openings 20 of the section 19 for the passage of removable holdfast devices 24 for detachably securing the sections of the frame members 16 in adjusted position. The horizontal legs of the sections of each frame member 16 provide a track. The tracks are arranged in parallel spaced relation. The vertical legs of the sections 18, 19 of each frame member 16 constitute a stop and they are arranged at the inner sides of the horizontal legs of such sections. The end members 17 are of like form and oppositely disposed and each includes a tubular section 25 and a tubular section 26. The outer end terminal portions of the sections 25, 26 are disposed at an inward inclination, as at 27, 28 respectively and seat against the inturned end terminal portions 22, 23 of the side frame members 16. The inturned end terminal portions of the sections 25, 26 of the end frame members 17 are compressed, as indicated at 29, Figure 6. A coupling piece 30 is employed for connecting an end terminal portion of a frame member 16 to an end terminal portion of a frame member 17 and in this connection attention is directed to Figure 6. The coupling 30 is positioned against the outer face of an end terminal portion of a frame member 16 and bears against and is seated upon an end terminal portion of a frame member 17. The coupling 30, end terminal portion 75 of a frame member 17 and end portion of a frame

member 16 are formed with registering openings 31, 32, 33 respectively. Extending through said registering openings is a headed retaining pin 34 which is removable.

The sections of each end frame member 17 are disposed in telescopic relation thereby providing for adjusting the width of the frame 15^a. Binding screws 35 are carried by the sections 25 and engage with the sections 28 of the end frame members 17 thereby retaining sections of an end frame member in adjusted relation.

The sections 25 and 26 of the end frame members 17 are provided with outwardly directed combined supports and coupling members 36 of like form and each consists of an upper plate 37, a lower plate 38 secured to the outer portion of a lower face of the plate 37, a shank 39 secured to the inner portion of the lower face of the plate 37 and a hook 40 depending from the outer end of the shank 39 and having its bill below and spaced from the plate 38. Each end frame member is provided with a pair of combined supporting and coupling members 36. Two of the said members 36 are riveted or otherwise secured, as at 41 to the sections 26 of the end frame members 17. The other two members 36 are riveted or otherwise secured, as at 42 to the sections 25 of the frame members 17. The members 36 which are secured to the sections 26 of the frame member 17 seat on and engage under the sections 10 of the adjustable end members 8 of the lowering device. The members 36 which are riveted to the sections 25 of the end members seat on and engage under the sections 9 of the end members of the lowering device. The said members 36 not only support the frame 15^a from the lowering device 1, but also detachably connect the frame 15^a to such device.

The section 25 of each end frame member 17 is formed with two spaced pairs of openings. The openings of each pair are indicated at 43, 44 and they are arranged in diametrically opposed relation with respect to section 25. Formed integral with the bottom of the section 25 of each end frame member 17 are depending collars 45 which form continuations of the edges of the openings 44. Threadably engaging with each collar 45 is a set screw 46 for a purpose to be referred to. The section 26 of each end frame member 17 is formed lengthwise thereof with a pair of aligned slots 47 with which the openings 43 and 44 communicate. Arranged over the section 25 of each end frame member 17 is a vertically disposed yoke 48 carrying a revoluble supporting roller 49. Integral with the bight 50 of the yoke 48 is a pair of vertically disposed parallel stems 51 which extend down through the pairs of openings formed in the section 25 and also through the slots 47 formed in the section 26. The stems 51 are vertically adjustable for the purpose of elevating and lowering the yoke 48. The stems 51 are secured in their adjusted position by the set screws 46. The purpose of adjusting the roller 49 is for aligning it with the body part of a slidable carriage 52.

The carriage 52 is slidable on and removable from the tracks provided by the side frame members 16 of the frame 15^a. The carriage 52 includes two spaced parallel pairs of spaced inverted yokes or hangers. The hangers of one pair are indicated at 53. The hangers of the other pair are designated 54. Secured to the upper end of each yoke is a post or standard 55. Mounted on each standard is a vertically adjustable collar 56. The collars 56 are arranged

in pairs and each pair is connected together by a bar 57 disposed in lengthwise relation with respect to the frame 15^a. The inner side of each collar 56 is formed integral therewith a depending hanger 58.

The carriage 52 includes a vertically adjustable body part. The collars 56, bars 57 and hangers 58 form elements of said body part and the latter also includes a pair of telescopic lengthwise adjustable supporting members 59, 60. The said supporting members are provided with means, as at 61 for retaining them in adjustable position. The members 59, 60 are disposed in transverse relation with respect to the frame 15^a and provide for adjusting the width of the body part of the carriage 52. Each supporting member is formed of a pair of sections 62, 63. The sections 62 of the supporting members are secured to one pair of hangers 58 and the sections 63 of the supporting members are secured to the other pair of hangers 58.

The body part of the carriage 52 also includes a skeleton arrester 64 of angle form which extends forwardly from the support 61. The arrester 64 is adjustable as to width and it includes a pair of oppositely disposed telescopic parts 65, 66 and each of which includes an upper portion 67 disposed in transverse relation with respect to the frame 15^a (Figure 4), a vertical portion 68 depending from the outer end of the portion 67 and a lower portion 69 (Figure 3) extending rearwardly from the lower end of the portion 68. The lower portions 69 of the telescopic parts 65, 66 are disposed longitudinally relative to the frame 15^a and are fixed at their rear ends with collars 70 secured to the sections 62, 63 of the member 60. The arrester 64 is provided with means, as at 71 for securing it in its adjusted position. The hangers 56 have revolubly connected therewith, as well as depending therefrom rollers or casters 72 which travel on the tracks provided by the horizontal legs of the side members 15 of the frame 15^a and are arrested from shifting outwardly relative to the frame members 15 by the vertical legs of said frame members.

It will be assumed that the casket placer 15 is in the position shown in Figure 1 and it is desired to arrange the casket relative to the device 1 for the purpose of the latter lowering the casket into the grave. When the casket placer is in the position shown in Figure 1 the roller 49 is aligned with the sections 63 of the members 59, 60. The pallbearers at the forward end of the casket position such forward end on the roller 49 and slide it on the body part of the carriage 52 to an extent to abut the arrester 65. The casket is shoved in a forward direction which causes the carriage 52 to travel in the same direction. The shifting of the casket is had until the belts 7 are arranged below and intermediate the ends of the casket. The latter is then lifted at its forward end and the carriage 52 removed and when removed the casket will seat upon the belts 7, and it is then lowered into the grave by means of the device 1. After the casket has been lowered the frame 15^a is detached from the lowering device 1 and dismantled.

With reference to the modified form of the casket placer shown in Figures 7 to 10 and generally indicated at 73, it includes a frame 74 having its side members 75 form a pair of spaced parallel tracks. The frame 74 includes a pair of end members 76. The side members 75 of the frame 74 are of tubular form and consist of a pair of telescopic sections 77, 78. The end mem-

bers 76 are of tubular form and formed of a pair of telescopic sections 79, 80. The side members 75 are of like form. The end members 76 are of like form. The side members 75 form tracks of convex cross section. The end terminal portions of each side member 75 are compressed, as indicated 81 and extend at an inward inclination. The end terminal portions 81 of each side member 75 are oppositely outwardly inclined. The end terminal portions of each end member 76 is compressed, as at 82 and they extend inwardly at an inclination. The end terminal portions of each end member 76 are oppositely outwardly inclined. Each end member 76 adjacent each end terminal portion thereof is shouldered, as at 83. The end terminal portions 82 of each end member 76 abut the inner faces of the side members 75. The end terminal portions 81 of the side members 75 are positioned against the outer faces of the end terminal portions 82 of the end members 76 and abut the shoulders 83. The end terminal portions 81 of the side members 75 are detachably secured to the end terminal portions 82 of the end members 76 by the holdfast means 84. The section 80 of the rear end member 76 of the frame 74 is provided with a vertically adjustable roller structure 85 for the same purpose and corresponding in construction to the roller structure shown by Figure 5.

The modified form shown in Figures 7 to 10 includes a carriage 86 for the same purpose of the carriage 52. The carriage 86 includes a body part formed of a pair of telescopic supports 87, 88 of like form and each formed of a pair of sections 89, 90. Fixed to the sections 89 of said supports is a plate 91 having front and rear depending flanges 92 secured to said sections 89 (Figure 9). Mounted on and fixed to the sections 90 is a plate 93 having front and rear depending flanges 94 fixed to said sections 90. The plate 93 is of less length than the plate 91. The plate 93 is also of less length than the sections 90. The sections 90 extend into the sections 89 and the carriage 86 is provided with a suitable means, as indicated at 95 for securing the sections 89 to the sections 90 when the carriage 86 is adjusted as to width. The sections 89 extend from the plate 91, as well as depend therefrom and provide hangers, as indicated at 96. The sections 90 extend from the plate 93, as well as depend from the latter and provide hangers, as indicated at 97. The hangers 96, 97 may be termed supports and which carry spindles 98 for rollers or casters 99 having concave grooves for travelling on the convexed tracks provided by the side members 75 of the frame 74. The carriage 86 includes a skeleton arrester 100 which extends from the sections 89, 90 of the support 88. The arrester 100 is substantially of the same form as the arrester 64 and is also adjustable relative to width with relation to the body part of the carriage 86. The sections of the arrester indicated 101, 102 are disposed in telescopic relation. Means, indicated at 103 is for the purpose of detachably securing the sections of the arrester in adjustable position.

The modified form of casket placer disclosed by Figures 7 to 10 includes spaced means for supporting the frame 74 from the lowering device and such means also provides for detachably connecting the frame 74 to the lowering device. The said spaced means are of like construction and each consists, with reference to Figure 10, of a bracket 104 formed of a horizontally disposed arm 105 and a hook 106 integral with the lower 75

face of the arm 105 intermediate the ends of the latter. The hook 106 depends from the arm 105 and has its bill 107 arranged below and spaced from the outer portion of the arm 105. The inner portion of the arm 105 has integral with its upper face a vertically disposed annular lug 108 having a concave upper face 109. The bracket 104 is formed with an opening 110 which extends through the rear end of the arm 105 and 5 also through the lug 108. Two of the brackets 104 are secured to and disposed in outwardly extended relation with respect to the section 77 of each side member 75. One of the brackets 104 is secured to and extended outwardly from the section 79 of each end member 76. A bracket 104 is secured to and disposed at outwardly extended relation with respect to the section 80 of each end member 76. The section 79 of each 10 end member 76 will have formed integral therewith a depending threaded bolt. Each section 80 of each end member 76 will be provided with a depending threaded bolt. Each section 77 of each side member 75 will have formed integral therewith a depending threaded bolt. Each of 15 said bolts is adapted to extend through the lug 108 and arm 105 in the manner as shown in Figure 10 and with the lug 108 bearing against that section of the frame 74 provided with the bolt (Figure 10). The said bolts are indicated at 111 20 (Figure 10) and the bolts are provided with clamping nuts 112 (Figure 10). When the brackets 104 are secured to the side and end members of the frame 74 the arms 105 are to seat on the side and end members of the lowering device 1 25 whereby the casket placer 73 will be supported from the lowering device and when the arms 105 are in the position as stated, the hooks of the brackets 104 engage under the sides and ends of the frame of the lowering device and detachably 30 connect the frame 74 to the device 1.

The modified form of the casket placer 73 shown by Figures 7 to 10 functions in the same manner as the casket placer illustrated by Figures 1 to 6. After the frame 74 is detached from 45 the lowering device 1 it is dismantled.

With reference to Figure 11 it discloses the use 50 of the carriage with respect to a vault base 113 which is to be supported at the top of the grave by the lowering device 1. The construction of the carriage is such that its body part will clear 55 the top of the base 113 when the casket is being placed in position over said base. When the carriage is employed to place the casket relative to a vault base on the lowering device the rollers 55 or casters 72 travel on the upper lengthwise marginal portions of base 113.

With reference to Figure 12 the modified form 60 of a track forming means consists of a pair of sections 114, 115 which constitute a side member of the frame of the placer. The sections 114, 115 65 are disposed in telescopic relation and are of angle shape in cross section to correspond to the contour of the sections 18, 19. The section 114 is hollow. The section 115 extends into the section 114. Otherwise than as stated the sections 114, 115 will conform in structure to the sections 18, 19 respectively.

What I claim is:

1. A casket placer for use in connection with a 70 casket lowering device having lowering belts, said placer including a flat rectangular frame providing parallel tracks lengthwise thereof, oppositely disposed spaced means extended laterally from the frame adapted to be detachably connected to said device for suspending the frame above and

in inwardly disposed relation with respect to the said device, a carriage travelling on said tracks, and an arrestor bodily carried by and extended forwardly from the carriage.

2. A casket placer for use in connection with a 5 casket lowering device of rectangular form having lowering belts, said placer including a flat rectangular frame providing parallel tracks lengthwise thereof, spaced means extended laterally from each end of the frame adapted to be 10 detachably connected to the ends of said device for suspending the frame above and in inwardly disposed relation with respect to said device, a carriage travelling on said tracks, and an angle-shaped arrestor of less width than the carriage 15 and bodily carried by and extended forwardly from the carriage.

3. A casket placer for use in connection with a casket lowering device of rectangular form having lowering belts, said placer including a 20 longitudinally and horizontally adjustable flat frame providing parallel tracks lengthwise thereof, spaced means extended laterally from each end of the frame for detachable connection to the ends of the device for suspending the frame 25 above and in inwardly disposed relation with respect to said device, a vertically and horizontally adjustable carriage travelling on said tracks, a horizontally adjustable angle-shaped arrestor of less width than the carriage and bodily carried 30 by and extended forwardly from the carriage, a vertically adjustable yoke connected to the rear end of said frame, and a supporting roller mounted in the yoke.

4. A casket placer for use in connection with a casket lowering device having lowering belts, said placer including a rectangular frame providing parallel tracks lengthwise thereof, spaced means extended laterally from the frame and being formed to abut the upper and lower faces 40 of said device to detachably connect the frame to said device to thereby suspend the frame above and in inwardly disposed relation with respect to said device, a carriage travelling on said tracks, and an arrestor bodily carried by and 45 extended from the front of the carriage.

5. In a casket placer, a carriage for travelling over and in inwardly disposed relation with respect to a casket lowering device, said carriage including two aligned spaced pairs of spaced vertically disposed mobile parts, the parts of each pair of parts being connected together, front and rear vertically and horizontally adjustable elements each formed of a pair of telescopic sections, each of said elements being slidably mounted on one of the parts of each of said pair of parts for connecting one pair of said parts to the other pair of said parts, an upstanding horizontally adjustable arrestor formed of a pair of vertically disposed angle-shaped sections having their upper 60 portions disposed in telescopic relation, each section of the arrestor connected at its lower end to a section of the front one of said elements, means carried by said elements for detachably securing them in adjusted positions, and means carried by the said arrestor for detachably securing it in its adjusted position.

6. A casket placer for use in connection with a casket lowering device of rectangular form having lowering belts, said placer including a flat 70 rectangular frame element formed of a pair of sectional lengthwise adjustable side members, a pair of sectional lengthwise adjustable end members and means for detachably connecting the ends of the side members to the ends of the end 75

members, means extended from the sections of the end members for detachable connection to the ends of said device for suspending the frame above and in inwardly disposed relation with respect to said device, the side members of said frame forming spaced parallel tracks, a horizontally extensible and retractible carriage travelling on said tracks and including front and rear ver-

tically adjustable portions, and a horizontally extensible and retractible arrestor of angle-shaped form having rearwardly extending lower portions fixed to the said forward portion of the carriage and upper horizontally disposed telescopic portions. ⁵

JOSEPH ROBERT SMETANA.
